UNITED STATES PATENT OFFICE.

CLARENCE S. NATHAN, OF NEW YORK, N. Y.

DESIGN FOR A CALENDAR.

SPECIFICATION forming part of Design No. 14,819, dated February 26, 1884.

Application filed November 28, 1883. Term of patent 3½ years.

To all whom it may concern:

Be it known that I, CLARENCE S. NATHAN, a citizen of the United States, residing at the city of New York, in the county of New York and State of New York, have invented and produced a new and original Design for Calendars, of which the following is a specification, reference being had therein to the accompanying drawing.

10 My invention is a design for calendars; and it consists, essentially, in a figure represented with pencil or brush as in the act of painting a picture, which picture forms the second main feature of said design. Besides these, 15 there are other accessory features—such as a background, a scroll, border, &c.—which may be varied without essentially changing my design. I arrange said design substantially as shown in the accompanying drawing, in which 20 there is a background representing a water-scene, with pond-lilies, &c., above which and on one side are butterflies. Standing centrally in front of this is the representation of a picture showing cherubs, flowers, &c., and 25 having an opening therein. Below this picture is a scroll, in the center of which appears an opening. On the lower right-hand corner

is a bracket filled in with arabesques, and supporting a female figure (which may represent the muse of art) with a palette in one hand, 30 while the other hand, containing a brush or pencil, is extended over or toward the picture, as if about to use the pencil on it, and extending across the front of the central picture is a scythe, which may have an oblong opening 35 therein. Surrounding the whole may be any suitable border.

What I claim as new is—

The design for a calendar herein shown and described, consisting of a representation of a 40 picture having delineated thereon cherubs, flowers, &c., and having an opening therein, a female figure, with a palette in one hand and brush or pencil in the other, and standing on a bracket, a scroll in the center of which is 45 an oblong opening, and a scythe also having an oblong opening therein, substantially as set forth.

In testimony whereof I affix my signature in presence of two witnesses.

CLARENCE S. NATHAN.
